SACHUSETTS, A CORPORATION OF MASSACHUSETTS.

LOCKING DEVICE FOR HANDLES.

1,165,658.

Specification of Letters Patent. Patented Dec. 28, 1915.

Application filed December 10, 1914. Serial No. 876,542.

To all whom it may concern:

Be it known that I, CHARLES E. FAIRBANKS, a citizen of the United States of America, residing in West Springfield, 5 county of Hampden, and State of Massachusetts, have invented certain new and useful Improvements in Locking Devices for Handles, of which the following is a specification.

- 10 This invention relates to locking devices for pump handles. While the invention is capable of general application to handles, it is especially adapted for use with the so-called dispensing pumps.
- 15 The dispensing pump, in general, comprises a pump cylinder, a piston reciprocable therein by a rack and pinion, and a crank-handle to turn the pinion. In addition, measuring stops are usually employed 20 with pumps of this class, which are so arranged that any thereof may be swung into the path of a projection on the rack. These stops limit the stroke of the pump piston to 25 various lengths, each of which corresponds to a definite unit of liquid measure. Such pumps are commonly used in garages, shops, and factories to dispense the various kinds 30 of oils. As usually arranged, these pumps are accessible to many people and, as the operating mechanism is of the simplest character, it is easily possible for unauthorized persons to obtain oil. Accordingly, it is desirable to provide means to prevent any but 35 the rightful persons from operating the pump.

An object of my invention is to provide a locking device adapted to lock the operating handle to the pump frame.

- 40 A further object is to provide a device of the class described which is arranged to prevent the disturbing of the lock and the removal of the operating handle.

One preferred form of my invention is illustrated in the accompanying drawings 45 in which,—

Figure 1 is a front elevational view of a portion of a common form of dispensing pump. Fig. 2 is a sectional view taken on the line 2—2 of Fig. 1 and looking in the 50 direction of the arrows. This view shows the handle locked to the frame of the pump. Fig. 3 is a sectional view of the handle taken on the line 3—3 of Fig. 2 and looking in the direction of the arrows. Fig. 4 is a view

similar to Fig. 3 showing the handle un- 55 locked and free for rotation.

Referring to the drawings, Fig. 1 shows the upper portion of a common form of dispensing pump. The upper portion of the frame is indicated at *a* which is supported 60 by an integrally formed upright *e* from the lower frame of the pump. The lower frame, and the cylinder, piston, and measuring stops connected therewith, are not illustrated as they are unnecessary to an understanding of the invention. *f* is the usual expansion pipe, which also serves as a supporting upright for the member *a* by reason of the set screw connection shown in Fig. 1. The rod *g* is the customary rod, which bears 70 the measuring stops not shown. The frame *a* is a hollow structure, which bridges across the space between the upright *e* and the expansion pipe *f*. Rotatably mounted within this frame on a shaft *d* is a pinion *c* which 75 meshes with a vertically disposed rack *b*. The latter is operatively connected to the piston rod of the pump in the usual manner. The shaft *d* has fixed thereon a crank-handle 1 by means of which the rack *b* may 80 be reciprocated in an obvious manner to operate the pump.

Referring now to Figs. 2 and 4, inclusive, it will be seen that the handle 1 is provided on its sides with webs 1', which extend 85 closely adjacent the frame *a* and form a channel-shaped pocket 13. Within this pocket and secured to the handle 1 is a lock 2, which has a spring latch 3. Slidably mounted and transversely arranged in the 90 handle 1 is a bolt 4, which has a notch 7 arranged to engage the latch 3, when the parts are in the relative positions shown in Fig. 2. A hole (see Fig. 3) is formed in the inner end of this bolt 4 to receive the free 95 end of a spring 6. The other end of this spring is secured to the lock, as shown in Figs. 2 and 4. It is to be noted that the spring 6 prevents the removal of the bolt 4, when the device is in unlocked position, as 100 shown in Fig. 4. Any forward pull on the bolt will cause the upper surface of the hole therein to force the spring 6 against the surface 5 of the handle 1 and thereby prevent removal of the bolt. The handle is secured 105 to the shaft *d* by an angularly arranged set-screw 11 which extends into the channel-shaped pocket 13.

Fig. 4 shows the handle in unlocked position. The spring 6 normally retains the bolt 4 in the retracted position there shown, and the latch 3 bears idly against the smooth 5 surface of the bolt 4. When, however, the handle is to be locked, it is brought upwardly until the bolt 4 comes into alignment with a hole 10 formed in the side of the frame *a*. The bolt is then pushed into 10 the hole 10, by pressing on the portion protruding from the handle, until the latch 3 snaps into the notch 7. The handle is now locked to the frame *a*, and it is impossible thereafter to manipulate the rack *b*. When 15 the handle is thus locked, the end of the bolt 4 is flush with the outer surface of the handle. Furthermore, the bolt 4 closely fits the hole in the handle 1 so that no room is left for the insertion of a "picking" tool to 20 force back the latch 3. Access to the lock 2 is also prevented since it lies in the pocket 13 closed by the hub for the shaft *d*, the walls 1', the wall 12, and the bolt 4. Therefore, manipulation of either bolt, latch, or 25 lock is prevented. The manner of mounting the handle 1 on the shaft *d* is such that it also cannot be removed when the handle is locked to the frame. Since the set-screw 11 extends into the pocket 13, it is inaccessible, 30 when the handle is locked, on account of the walls 1' and 12, which extend closely adjacent to the frame *a* as already described. It will, therefore, be seen that my locking device is arranged to prevent the use of the 35 pump by any one not provided with a key. The latter, when applied to the lock 2, withdraws the latch 3 from the notch 7, and the spring 6 withdraws the bolt 4 from the hole 10 in an obvious manner. Thus, I have pro- 40 vided a simple means of locking the operating mechanism of a pump. Moreover, this locking device is so arranged that tampering with the lock is effectually prevented. It is recognized that various modifications 45 may be made in the structure described without departing from the scope of my invention which is defined in the appended claims.

What I claim is:—

50 1. A locking device for a pump, comprising

ing, in combination, a frame, pump actuating means therein, a handle arranged to operate said means, said handle formed with a pocket opening toward said frame, a locking device in said pocket movable into said 55 frame, to lock said handle and mechanism within said pocket operable by a key from without the pocket, to release said handle, whereby the latter may be turned to actuate said means, said pocket arranged to be entirely closed by said frame, whereby said device and mechanism are inaccessible when the handle is in locked position.

2. A locking device for a pump handle, comprising, in combination, a frame formed 65 with an opening therein, pump mechanism mounted in said frame, a handle to actuate said mechanism movable adjacent said frame, a pocket formed in said handle opening toward said frame, a bolt in said 70 pocket operable from without the handle to enter said opening to lock the handle to the frame, and a spring lock to retain the bolt in locked position, said lock being operable by a key from without the handle to retract 75 said bolt and release said handle, said pocket arranged to be closed by said frame when the handle is in locked position; whereby the lock and bolt are inaccessible.

3. A locking device for a pump handle, comprising, in combination, a frame formed with an opening therein, a shaft mounted in said frame, pump mechanism operable therefrom, a handle on said shaft formed with a pocket opening toward said frame, a bolt in 80 said handle and within said pocket adapted to enter said opening to lock said handle, a lock in said pocket to hold the bolt in locked position, said lock being operable by a key from outside said handle to release said bolt, 85 means thereafter to withdraw said bolt from said opening, and means to secure said handle to said shaft operable from within said pocket, said pocket arranged to be closed by said frame when the handle is in locked po- 90 sition.

CHARLES E. FAIRBANKS.
